E. R. HAMILTON

COLLAPSIBLE TUBE HOLDING AND COMPRESSING DEVICE

Filed April 26, 1926

Patented Feb. 22, 1927.

UNITED STATES PATENT OFFICE.

EARL R. HAMILTON, OF PEKIN, INDIANA.

COLLAPSIBLE-TUBE HOLDING AND COMPRESSING DEVICE.

Application filed April 26, 1926. Serial No. 104,718.

The invention relates to improvements in devices for holding and compressing collapsible tubes, such as those in which various commodities are marketed in paste form.

5 One object of the invention is to provide a tubular casing to contain a collapsible tube and to form this casing with novel means for engaging the tube to assist in holding it properly in place.

10 Another object is to provide novel means for compressing the tube to discharge its contents.

The tube-compressing means, in the present disclosures includes a ball exposed through a slot in the tubular casing to be manipulated by the user's thumb to compress the tube, and a further object is to provide a novel guard which prevents said ball from dropping out of the casing if the latter is inverted, said guard being movable to an inoperative position by engagement with said ball under force and being self-held in such position to permit removal of the ball, and an emptied tube, insertion of a new tube, 25 and re-insertion of the ball.

A still further object is to provide the casing with internal means into engagement with which, the tube is forced under the compressing operation, thus establishing an anti-slipping connection between the tube and casing and thus preventing any longitudinal creeping of the tube.

A still further aim is to provide a device of the class set forth which is exceptionally simple and inexpensive, yet will be highly efficient and in every way desirable.

With the foregoing in view, the invention resides in the novel subject matter herein-after described and claimed, the description being supplemented by the accompanying drawing.

Fig. 1 is a side elevation of a tube-holder and compressor constructed in accordance with the invention.

45 Fig. 2 is a longitudinal sectional view on the plane of line 2-2 of Fig. 1.

Fig. 3 is a transverse section on line 3-3 of Fig. 1.

50 Fig. 4 is a longitudinal sectional view showing a slightly different form of construction and illustrating one manner of connecting an applicator with the tubular casing and the compressible tube.

55 Fig. 5 is a detail sectional view illustrating a still further way of connecting the applicator with the casing and tube.

In the form of construction illustrated in Figs. 1, 2 and 3, the numeral 6 designates an elongated cylindrical casing formed of any desired material such as sheet metal. 60 One end of this casing may well be open although it could have an appropriate removable cap if desired. The other end 7 of the casing 6 is formed with a central opening 8, and this end 7 is preferably disposed oblique to the axis of the casing, as shown. Adjacent the end 7, the casing 6 is constricted as indicated at 9 and this constricted portion is provided with an inwardly pressed circumferential part which 70 forms an internal ridge 10.

A collapsible tube 11 is receivable in the casing 6 and a discharge neck 12 of this tube passes through the opening 8 so that the usual cap 13 is exposed at the exterior of 75 the casing to be removed whenever contents are to be discharged. Before inserting the tube 11, the end thereof adjacent the neck 12, is preferably rolled between the thumb and finger so that its diameter is somewhat 80 reduced. Thus, this reduced end of the tube may readily pass the ridge 10 but when the upper end of the tube is later compressed somewhat and its contents thus forced downwardly, this reduced lower end is again expanded 85 so that it tightly engages the ridge 10 and is by the latter held in proper place in the casing.

The casing 6 is formed with a longitudinal slot 14 and a freely movable ball 15 90 of any desired material, is provided within said casing, for compressing the tube 11, a portion of said ball being exposed through the slot 14, so that with his thumb, the user may force the ball 15 inwardly and at the 95 same time urge it toward the neck 12, thus effectively compressing the tube 11 and discharging the contents thereof, the cap 13 being of course detached at this time.

A guard is provided to prevent accidental 100 dropping of the ball 15 from the casing 6 by gravity, said guard being preferably in the form of a spring arm 16 within the casing and suitably secured to the wall of the latter, the outer end of this arm being provided with a shoulder 17 which is adapted 105 to snap over the open end of the casing as shown in dotted lines in Fig. 2, when the ball 15 and a used tube 11 are to be removed. Mere outward forcing of the ball 15 against the spring arm 16, forces the latter toward the wall of the casing 6 and 110

causes its shoulder 17 to snap over the end of the casing, so that the arm will be held in this position while the ball and the old tube are being removed, while a new tube is

5 being inserted, and while said ball is being replaced. Then, the shoulder 17 is manually disengaged from the casing 6 and the guard arm returned to the full line position of Fig. 2.

10 I provide the interior of the tube 6 with a plurality of longitudinally spaced shoulders 18 which are preferably formed by outwardly pressing portions of said casing throughout the circumference of the latter so as to stiffen said casing while forming the shoulders. When the tube 11 is compressed by operation of the ball 15, portions of said tube are distorted into engagement with these shoulders, so that the latter hold 15 the tube against any longitudinal compression or creeping. Thus, possible longitudinal collapse of the tube and inconvenience resulting therefrom, are obviated.

15 The construction shown in Fig. 4 is about the same as that so far described, with the exception that the constricted portion 9^a is not quite as small, and the ridge 10^a is spaced a greater distance from the casing end 7^a. This is done in order that an 20 adapter 19 may pass outwardly through the central opening 8^a of the end 7^a to carry an applicator 20. This applicator has a threaded engagement with the adapter 19 and contacts with the outer side of the end 25 7^a, and the inner end of said adapter is provided with a head 21 which seats tightly against the inner side of said end 7^a. A very rigid connection is thus established between the casing 6^a, the tube 11^a and the 30 applicator 20, permitting rough usage without disarranging the parts. The applicator 20, for purposes of illustration, is practically identical with that shown in my U. S. Patent No. 1,572,514 of Feb. 16, 1926.

35 45 When the contents of the tube 11^a are exhausted, the applicator 20 is unthreaded from the adapter 19, the compressing ball 15^a is removed, and the tube 11^a and adapter are bodily withdrawn as a single unit. This adapter is then detached from the old 40 tube and applied to a new one, and this new tube with the adapter are then downwardly inserted into the casing 6^a. The applicator 20 is then rethreaded upon the 45 adapter 19 and the device is in condition for further use.

50 If a less rugged connection can be satisfactorily used between the casing and the applicator, for instance, when the collapsible tube merely contains library paste, the construction disclosed in Fig. 5 may be employed. This construction is practically identical with that shown in Fig. 4, with the exception that the discharge neck of the 55 collapsible tube 11^b passes through the cen-

tral opening 8^b of the casing end 7^b, and the applicator 20^b is threaded directly onto said discharge neck.

Any form of the invention is simple and inexpensive, yet is efficient, easy and convenient to operate, and generally desirable. The details disclosed are preferably followed, but within the scope of the invention as claimed, variations may be made.

I claim:

1. In a tube holder and compressor, a tubular casing adapted to contain a compressible tube, said casing having a longitudinal slot, a tube-compressing ball within the casing having a portion exposed through said slot whereby the ball may be manually moved to compress the tube and discharge its contents, said casing having an open end through which said ball is insertible and removable, a guard for said open end carried by the casing and adapted to normally prevent movement of the ball from said casing, said guard being movable outwardly toward the casing by forcible engagement of the ball with the guard, and means for holding said guard in released position while removing the ball, changing tubes and reinserting said ball.

2. In a tube holder and compressor, an elongated tubular casing adapted to contain a compressible tube, said casing having a longitudinal slot, and a tube-compressing ball within the casing having a portion exposed through said slot whereby the ball may be manually moved to compress the tube and discharge its contents, said casing having an open end through which said ball is insertible and removable, a guard for said open end carried by the casing and adapted to normally prevent movement of the ball from the casing, said guard being movable outwardly to released position by forcible engagement of the ball with the guard, said guard having a yieldable portion engageable with the casing and adapted to hold the guard in released position while the ball is being removed, tubes changed, and said ball reinserted.

3. In a tube holding device, an elongated tubular casing having means at one end to encircle and embed itself in the body of a collapsible tube at a point spaced inwardly from the neck of the tube and hold the tube in the casing when the former is forcibly expanded against said means.

4. In a tube holder and compressor, a tube-receiving casing having longitudinally movable means for compressing the tube against the wall of said casing, and a plurality of internal shoulders on said casing wall into engagement with which the tube is distorted by said compressing means.

5. A structure as specified in claim 4; said shoulders being formed by outwardly

pressed circumferential portions of the tu-
bular casing.

6. A tube holding and compressing device
comprising an elongated tubular casing
closed at one end and having an opening in
said end, an adapter passing through said
opening and having a threaded outer end,
the inner end of said adapter being designed
for engagement with the outlet neck of a

collapsible tube within the casing and hav-
ing a head contacting with the inner side of
said closed end, and an applicator threaded
on the outer end of said adapter, said ap-
plicator contacting with the outer side of
said closed end.

In testimony whereof I have hereunto af-
fixed my signature.

EARL R. HAMILTON.
